FIGURE TOY

Miriam Blum Richman, Cincinnati, Ohio

Application July 6, 1936, Serial No. 89,172

6 Claims. (Cl. 46—151)

This invention relates to improvements in figure toys, and the primary object of the present invention is to provide a figure toy or doll which is of novel construction and capable of presenting selectively any one of a plurality of different figures or characters.

More particularly, the present invention aims to provide a multiple figure toy or doll including a hollow member representing a portion of the body of an animal and having a plurality of openings, and a plurality of elements carried by and stored within said hollow member, said elements being capable of being selectively withdrawn from said hollow member through the respective openings to complete the body of the animal or figure or to complete and enhance said body or figure, said elements further being of different form or kind to provide for the selective presentation of any one of a plurality of different figures or characters.

With the above general objects in view, and others which will become apparent as the nature of the invention is better understood, such invention consists in the novel form, combination and arrangement of parts hereinafter more fully described, shown in the accompanying drawing, and claimed.

In the drawing:

Figure 1 is an enlarged perspective view of a form of figure toy embodying the present invention, with the withdrawable elements inserted and stored within the hollow member of the toy.

Figure 2 is a view of the toy shown in Figure 1, partially in perspective and partially in front elevation, with two of the withdrawable elements withdrawn from the hollow member to present one of the plurality of different figures or characters; and

Figure 3 is an enlarged fragmentary section taken on the plane of line 3—3 of Figure 2.

Referring in detail to the drawing, the illustrated embodiment of the present invention consists of a multiple doll including a hollow member 5 representing the head of a human figure including a cylindrical wall 6 and circular end or front and rear walls 7 and 8. These walls may be formed of any suitable material such as stiff cardboard, buckram, etc. Said walls are provided with a fabric covering 9 of attractive color, and on the outer surface of the portion of the cover 9 for the front wall 7 may be suitably provided or depicted the features of the head, such as the mouth 10, nose 11, eyes 12 and cheek rouge 13. A soft padding is preferably provided as at 14

between the front wall 7 and its covering 9. Hanks of cord may be suitably provided on and stitched or otherwise secured to the upper portion of the hollow member 5, as at 15 to represent the hair. A plurality of openings or circumferentially elongated slots 16 are provided in the lower portion of the wall 6, while similar openings or slots 17 are provided in the top or upper portion of said wall 6.

Carried by and arranged within the lower portion of the hollow member 5 are a plurality of elements 18 capable of being withdrawn from the member 5 through the respective slots 16, as well as returnable within the member 5 through said slots 16. The elements 18 differ in form or kind, and each, when withdrawn from the member 5, is adapted to complete the figure or body of the doll. For instance, one element 18 may be of a form to represent the torso, legs and arms of a doll suitably dressed, another of the elements 18 may represent a different form of torso or a differently posed and dressed lower portion of the body of a figure, and so on. Thus, by selectively withdrawing the elements 18 from the hollow member 5, any one of a number of different figures or characters may be presented. As shown the elements 18 are formed in proper shape and character out of fabric which may be conveniently folded and tucked into the member 5 through the slots 18 as well as suitably engaged and withdrawn from said member 5 through said slots 16. To prevent detachment of the elements 18 from the member 5, suitable provision may be made, such as stitching of said elements to the wall 6 about the respective slots.

Another series of elements 18a are carried by and arranged or stored within the upper portion of the hollow member 5, which latter elements may represent different kinds or forms of headwear and accessories such as combs, ribbons, etc. These elements 18a can be selectively withdrawn from the member 5 through the respective slots 17 for the purpose of differently enhancing the head member 5.

If desired, the interior of the hollow member 5 may be divided into a number of separate compartments, each adapted to receive one of the elements 18 or 18a. This may be done in different ways, but accomplishment of the result is illustrated as had by dividing the interior of said member 5 through the medium of a plurality of spaced partitions 19 extending parallel with the front and rear walls 7 and 8 and disposed in planes intermediate adjacent openings 16 and adjacent openings 17. Additional horizontal

partitions 20 may be provided to separate the elements 18 from the elements 18a, and the compartments 19 and 20 may be formed of suitable stiff material such as buckram.

5 From the foregoing description, it will be seen that the present invention provides a novel form of multiple figure toy or doll which may be conveniently transformed to present any desired one of a plurality of figures or characters and to provide for differently enhancing such characters. It will be understood, however, that the illustrated embodiment of the invention is simply shown and described by way of example to reveal the general ideas or principles involved. It is 10 therefore pointed out that the invention is susceptible of many and varied modifications and changes without departing from the spirit and scope of the invention as claimed. For instance, it will be obvious that facial features may be depicted or otherwise provided on more than one side or surface of the hollow member to increase the number of different figures or characters which may be presented. It will also be apparent that the hollow member 5 need not necessarily 15 represent the head of a human figure or other animal. In other words, the hollow member 5 may consist of any selected portion of the body of a human figure or other animal, the completion and enhancement of which may be effected 20 by the elements 18 and/or 18a. For convenience in carrying the toy, a suitable hand loop or handle 21 may be provided, which handle is shown in the nature of a piece of ribbon extending over the top of the member 5 and attached at its ends 25 to the opposite side of said member 5.

A figure toy or doll embodying the present invention affords variety of amusement and the opportunity of a child to practice creative talent and good habits relative to the care and orderly 30 placing of the elements 15, 18 and 18a.

Having thus described my invention, what I claim as new is:

1. A multiple figure toy comprising a hollow member representing at least a portion of the 45 body of an animal and provided with a plurality of openings, and a plurality of elements arranged within and selectively withdrawable from said hollow member through the respective openings of the latter to enhance said body of the animal, 50 said elements differing in form or character so as to present, in connection with said hollow member, a plurality of figures or characters.

2. A figure toy including a hollow member representing at least a portion of the body of an 55 animal and having a plurality of openings in the top thereof and a plurality of openings in the bottom thereof, and a plurality of elements arranged within said hollow member and selectively withdrawable from the latter through the 60 respective openings to enhance said representation of the body of an animal, said elements dif-

ferring one from the other so as to provide for the selective presentation of any one of a plurality of different figures.

3. A multiple figure toy comprising a hollow member representing at least a portion of the body of an animal and provided with a plurality of openings, a plurality of elements arranged within and selectively withdrawable from said hollow member through the respective openings of the latter to enhance said body of the animal, 10 said elements differing in form or character so as to present, in connection with said hollow member, a plurality of figures or characters, and means providing a plurality of compartments within said hollow member each arranged to receive one of said elements. 15

4. A figure toy including a hollow member representing at least a portion of the body of an animal and having a plurality of openings in the top thereof and a plurality of openings in the bottom thereof, a plurality of elements arranged within said hollow member and selectively withdrawable from the latter through the respective openings to enhance said representation of the body of an animal, said elements differing one from the other so as to provide for the selective presentation of any one of a plurality of different figures, and means providing a plurality of compartments in the upper portion of and a plurality of compartments in the lower portion of said hollow member, each of said compartments being arranged to receive one of said elements. 20 25

5. A multiple doll comprising a hollow member representing the head of a human figure and having a plurality of openings in the bottom thereof, and a plurality of elements arranged within and selectively withdrawable from said hollow member through said openings thereof, 30 said elements being of a form to complete the human figure and differing from each other for selectively presenting any one of a plurality of different characters. 35 40

6. A multiple doll comprising a hollow member representing the head of a human figure and having a plurality of openings in the bottom thereof, a plurality of elements arranged within and selectively withdrawable from said hollow member through said openings thereof, said elements being of a form to complete the human figure and differing from each other for selectively presenting any one of a plurality of different characters, said hollow member further having a plurality of openings in the top thereof, and further elements arranged within and selectively withdrawable from said hollow member through the latter openings to provide selectively useable different forms of headwear or accessories for enhancing the head represented by said hollow member. 45 50 55 60
